UNITED STATES PATENT OFFICE

ROY E. CASTETTER, OF WYOMING, OHIO

DESIGN FOR AN AQUARIUM

Application filed July 16, 1931. Serial No. 40,567. Term of patent 7 years.

To all whom it may concern:

Be it known that I, ROY E. CASTETTER, a citizen of the United States, residing in Wyoming, in the county of Hamilton and State of Ohio, have invented a new, original, and ornamental Design for an Aquarium, of which the following is a specification, reference being had to the accompanying drawings forming part thereof, in which:

Fig. 1 is a side elevation of an aquarium showing my new design.

Fig. 2 is a perspective view of the same.

Fig. 3 is a plan view of the same.

The wall of the aquarium is made of such material, for instance glass, that fish and other contents in the water in the aquarium may be viewed through said wall.

I claim:

The ornamental design for an aquarium, substantially as shown and described.

ROY E. CASTETTER.
